Mark A. Peters.

UNITED STATES PATENT OFFICE.

ULRICH A. PETERS, OF PITTSBURG, PENNSYLVANIA.

REVERSING-VALVE.

No. 888,736.

Specification of Letters Patent.

Patented May 26, 1908.

Application filed July 18, 1907. Serial No. 384,439.

To all whom it may concern:

Be it known that I, ULRICH A. PETERS, a citizen of the United States, residing at Pittsburg, in the county of Allegheny and State of Pennsylvania, have invented a new and useful Improvement in Reversing-Valves, of which the following is a full, clear, and exact description, reference being had to the accompanying drawings, forming part of this specification.

My invention relates to that class of valves used more particularly in connection with regenerative furnaces whereby the current of the gases therethrough may be reversed, and particularly contemplates the provision of a simple and efficient construction of this character in which no flat or other plates, which might warp under the alternate expansion and contraction, are used.

My invention further contemplates the provision of a novel construction in which a direct connection between the gas box and the stack flue is impossible, and further in which sealed movable parts are embodied with means for operating the same to admit sufficient air to the valve to allow the gas to be consumed in the furnace.

My invention further and specifically resides in the following features of construction, arrangement and operation to be hereinafter described with reference to the accompanying drawings, forming a part of this specification, in which like numerals are used to designate like parts throughout the several figures, and in which

Figure 1 is a view half in top plan of the entire apparatus, and half in plan of the base casting with the valve removed. Fig. 2 is a vertical sectional view through the valve on the line I—I of Fig. 1. Fig. 3 is a vertical sectional view through the entire apparatus on the line II—II of Fig. 1. Fig. 4 is a sectional view through a portion of the base casting and the valve, Fig. 5 is a fragmentary elevation of a portion of the valve, and partly in section, and Fig. 6 is a sectional view, partly in elevation illustrating the valve mounting.

In the practical embodiment of my invention I provide a frusto-conical base casting 1, having a circular rail 2 at its upper outer edge and provided with circular sand and water seal troughs 3 and 4 at its inner lower edge and adjacent the rail 2, respectively. The casting 1 is further provided with a circular base opening A leading to the re-

generator stack and with oppositely disposed openings B and C in its inclined sides leading to the regenerator flues and through which the gases pass alternately to and from the furnace.

The valve proper 5 comprises a two chambered cylindrical casing divided by an inclined wall 5°, and provided with outwardly extending segmental hoods, oppositely disposed and leading one from each of said chambers and terminating in openings E and F adapted to be alined with the openings B and C of the casting 1. The valve 5 is also provided with cover plates 6 extending angularly upwardly from the base thereof and occupying the space between said hoods, and with a depending flange 8 entering the sand seal trough 3 adjacent its lower circular opening G alining with the opening A of the casting 1, the outer edges of said hoods and said cover plates being continuously formed with flanges 9 entering the water seal trough 4 of the casting 1. The hoods are provided along each side the roof with seals 10 for the cover plate 6, and supporting the journals 21 of wheels 7 pivotally mounted therein, and by means of which the valve 5 is supported to rotate, set screws 15 threaded through a portion of said hoods, serving to adjust said journals 21 to a proper seating and balanced rotation of the valve. The hoods are further provided with covered cleaning or explosion doors 13, while the casting 1 is provided with sand pockets 14 leading into its sand seal trough 3, having removable covers 14° resting upon the cover plate 6, as shown particularly in Fig. 4 and briefly indicated in Fig. 2. The valve 5 is provided at its upper edge surrounding its upper opening D with a water seal trough 12 into which the flange 12°, surrounding the lower opening of the gas box 11, projects, and with a plurality of studs 18 extending outwardly from adjacent said edge, on which brackets 18° are mounted which support the said gas box 11. The valve 5 is rotated in any desired manner as by a bevel gear 16 engaging a circular rack 17 upon said valve 5.

In the practical operation of my invention the valve 5 is rotated to alternately register its hood openings E and F with each of the openings B and C through the base casting 1 communicating with the regenerator flues, thus putting said flues alternately in communication with the gas supply and with the stack as will be seen.

In the further operation of my invention in connection with double regenerator chambers for gas and air, I provide pivotal levers 20° mounted on the sides of the gas box 11 5 and provided with a pivotal depending arm 20 having a hooked lower end resting adjacent the rail 2 and adapted to engage a plate 19 extending from the edge of the cover plates 6 over said rail. Thus the cover plates 6 may be raised slightly from their seal to admit a sufficient quantity of air to consume the gas between the valve and the furnace.

Having thus described my invention what 15 I claim is:

1. The combination with a valve having a pair of flanges, of a fixed frusto-conical base plate, having a pair of seal troughs into which said flanges project, substantially as described.
2. The combination with a valve comprising a two-chambered casing having segmental flue openings leading from said chambers, of a fixed frusto-conical base plate having oppositely disposed flue openings in its 25 inclined sides, corresponding to said segmental valve openings, substantially as described.
3. The combination with a valve comprising a two-chambered casing having segmental flue openings leading from said chambers, and having top and bottom openings communicating therewith, of a fixed frusto-conical base plate having oppositely disposed flue openings in its inclined sides corresponding to said segmental flue openings, and having a central base opening communicating with said bottom opening of said valve, substantially as described.
4. In a valve of the character described, 40 the combination of a casing having segmental hoods extending therefrom, a pair of cover plates movably mounted between said hoods and extending angularly upwardly from said casing, and a frusto-conical base plate upon

which said casing is adapted to rotate having flue openings to register with said hoods and said cover plates, substantially as described.

5. In a valve of the character described, the combination of a casing having segmental hoods extending therefrom and forming flue openings, a pair of cover plates movably mounted between said hoods, said casing, hoods and cover plates having extending flanges, and a frusto-conical base plate upon 55 which said casing is adapted to rotate, having seal troughs to receive said flanges, and having flue openings to register with said hoods and said cover plates, substantially as described.

6. In a valve of the character described, the combination of a casing having segmental hoods extending therefrom and forming flue openings, a pair of cover plates movably mounted between said hoods, a base plate 65 upon which said casing is mounted to rotate, having flue openings to register with said cover plates and said hoods, and means for raising said cover plates, substantially as described.

7. In a valve of the character described, the combination of a casing having an inlet and provided with extending hoods forming flue openings therethrough, of a fixed base plate having openings to register with said 75 flue openings, rollers carried by said casing and traveling upon a portion of said base plate, said rollers having their journals pivotally adjustably mounted upon portions of said casing; and means for adjusting the same, substantially as described.

Signed at Pittsburg, in the county of Allegheny, and State of Pennsylvania, in the presence of two witnesses, this 17th day of July, 1907.

ULRICH A. PETERS.
